UNITED STATES PATENT OFFICE.

ERNEST G. SHINNER, OF CHICAGO, ILLINOIS.

DISPLAY-RACK.

1,267,917.

Specification of Letters Patent.

Patented May 28, 1918.

Application filed August 16, 1917. Serial No. 186,452.

To all whom it may concern:

Be it known that I, ERNEST G. SHINNER, a citizen of the United States, residing at Chicago, in the county of Cook and State of Illinois, have invented certain new and useful Improvements in Display-Racks, of which the following is a specification.

My invention relates to improvements in display racks for use in stores, shops and the like.

In butcher-shops, or meat stores, racks are used for display of the purveyors' wares, such as smoked hams, sides, shoulders and other similar commodities.

Heretofore it has been the custom to have display racks of this general character made by local artisans and built in and permanently attached to the walls of the rooms in which the store products are to be displayed.

One of the objects of my invention is to provide an improved display rack that is divided into uniform like separable sections, capable of being quickly and easily assembled and as quickly knocked down and packed in relatively small compass for storage or shipment, and which may be erected and put together by unskilled labor.

Another object of my invention is to fashion the parts of the rack so as to provide smooth, rounded surfaces devoid of dust pockets and in which all of the parts are easily accessible for cleaning.

Other and further objects of my invention will become readily apparent, to persons skilled in the art, from a consideration of the following description when taken in conjunction with the drawings, wherein:—

Figure 1 is an end elevation of an erected sectional rack.

Fig. 2 is an enlarged central sectional view of parts of two interconnecting support sections.

Fig. 3 is an enlarged front view of the rack showing a fragment thereof.

Fig. 4 is a detail.

Fig. 5 is a front view of the erected rack.

In all of the views the same reference characters are employed to indicate similar parts.

My sectional rack is especially designed to be attached to the premises by means that permit its ready removal without damage to the premises and therefore for this reason, it does not become a permanent unremovable

fixture, and the property of the landlord when the tenant vacates.

My rack may be erected by an unskilled workman or by tenant and used by him during his occupancy of the premises and taken down and carried away by him when he gives up possession of the premises.

The capacity of the rack may be varied by the number of sections in vertical sequence in the supports, and the length of the structure.

In the preferred embodiment of my invention there is a plurality of vertical supports 10, each made up of a number of sections 11, 12, 13 and 14. Each vertical support is, preferably, made of standard pipe of uniform diameter, the base section 11 is supported in the flanged socket 15 which may be secured to the floor by screws 16. At a uniform distance from the floor is secured to each of the base sections 11, a bracket 17 for supporting a shelf 18. The shelf 18 is preferably made of marble plate, and a vertically disposed marble plate 19 is located at the back of the shelf and is secured to the vertical base sections 11. The pipe, or tube 12 terminates, as at 20, and the section 13 is provided on its lower end with a socket 21 which consists of a short section of tubing secured to the section as by spot welds or rivets 22. The projecting end 21 forms a tenon for telescopic connection with the end of the section there below. In like manner the section 14 is provided with a similar tenon for telescopic association with the upper end of the section 13 and section 12 is joined to section 11 by a tenon and socket of like character. Section 12 is provided with a curved bracket 23 having its free end downturned as at 24, and welded or otherwise secured to the vertical tube of section 12 in like manner section 13 has an outstanding downwardly curved bracket 25, curved on a longer radius to extend beyond the bracket 23 and section 14 has a similar bracket 26 outstanding farther than bracket 25.

Each of the composite, vertical supports 10 is secured to the side wall 27 by means of screws 28, which pass through spacing blocks 29, the contacting surface of which is curved to correspond with the curvature of the tubes of the vertical supports.

In Fig. 5 I have shown four vertical com-

posite supports 10—10 arranged in parallel vertical planes. These supports are substantially alike and correspond with that shown in side elevation in Fig. 1. The bracket members are held together by tenon and mortise slip joints, as shown in Fig. 2, and the lower bracket is secured in like manner to the base member 12. The free end of each bracket, 23, 25 and 26 is closed by a metal plug 30, riveted or otherwise secured therein, to receive a screw 31. A wooden stringer 32, is secured to the under end of the brackets by means of screws, 31 passing therethrough and into the inserted, threaded plug 30. These stringers, 32, are bored, uniform distances apart, equal to the distances of separation of the vertical members 10, to receive the screws 31 so as to firmly hold the vertical supports 10 in vertical alinement. Hooks 33 may be placed on the stringers at frequent intervals. An ornament 34 may be placed on the upper end of each of the vertical supports 10 to add to the artistic design and appearance of the rack. T-iron stringers 35, of which there may be two, are supported by the brackets 17 and serve as cantining supports for the marble shelf 18. At the points where the T-iron stringers rest upon the brackets, the vertical ribs are cut away, as at 36, so as to permit the horizontal ribs 37 to rest firmly upon the upper surface of the brackets.

It will be observed that all of the surfaces of the rack are smooth and rounded and that there are no crevices or pockets for the lodgment of dirt or dust and that it may be easily and readily cleaned; when the rack is painted white and enameled, it presents a neat, artistic and sanitary appearance.

Having described my invention, what I claim is:

1. A display rack comprising a series of vertical, composite superposed supports, each divided into a series of sections separably connected together; each section having an outwardly extending bracket and means for connecting stringers to the free ends of said brackets to connect the supports together;

stringers for connecting said brackets; hooks spaced apart on the stringers and a base support for the superposed sections.

2. A display rack comprising a series of vertical, composite superposed supports, each support divided into a series of sections separably connected together by tenon and socket joints; a curved outwardly-extending bracket, secured to each section, having its free end downturned; a threaded plug in the free end of each bracket; stringers having a series of spaced-apart perforations to receive attaching screws; attaching screws taking through said perforations into said plugs to hold the supports properly spaced apart and hooks on said stringers.

3. A display rack comprising a series of vertical, composite supports, each support divided into a series of longitudinal sections separably connected together by slip joints, the base section of each support provided with means for supporting a shelf; the superposed sections of said supports each having an outwardly projecting bracket to which stringers may be connected; stringers connecting the brackets of each section together and having spaced-apart hooks at intervals along said stringers.

4. A display rack comprising a series of vertical, composite supports, each divided into a series of longitudinal sections separably connected together by detachable joints; and base sections of each support provided with means for supporting a shelf; each superposed section of each support, having an outwardly projecting bracket to which hook supporting stringers may be connected; a floor socket for each base section; spacing blocks, one for each section, to separate the supports from a wall and screws taking through the supports and through the spacing blocks, respectively, to hold said supports in upright position against said wall.

In testimony whereof I hereunto set my hand.

ERNEST G. SHINNER.
